H. SCHAECHTERLE ET AL.
INCUBATOR EGG TRAY.
FILED DEC. 6, 1921.

Henry Schaechterle,
John Schaechterle, INVENTOR.

ATTORNEY.

UNITED STATES PATENT OFFICE.

HENRY SCHAECHTERLE AND JOHN SCHAECHTERLE, OF FRIEND, NEBRASKA.

INCUBATOR EGG TRAY.

Application filed December 6, 1921. Serial No. 520,281.

To all whom it may concern:

Be it known that we, HENRY SCHAECHTERLE and JOHN SCHAECHTERLE, citizens of the United States and Russia, respectively, 5 residing at Friend, in the county of Saline and State of Nebraska, have invented certain new and useful Improvements in Incubator Egg Trays, of which the following is a specification.

- 10 This invention relates to incubator trays, and has for one of its objects to provide a simply constructed device of this character of improved construction and increased efficiency and utility.
- 15 Another object of the invention is to provide a device of this character constructed wholly of metal and of easily separable parts so that renewal and repairs can be easily made and the parts readily cleansed 20 and disinfected.

With these and other objects in view, the invention consists in certain novel features of construction as hereinafter shown and described and then specifically pointed out 25 in the claims, and in the drawings illustrative of the preferred embodiment of the invention;

Figure 1 is a plain view of the device complete.

30 Fig. 2 is a transverse section on the line 2-2 of Fig. 1.

Fig. 3 is an enlarged sectional detail illustrating the construction more fully.

Fig. 4 is a plan view, enlarged, of portions 35 of the egg holding cups illustrating the construction.

Fig. 5 is a perspective view, enlarged, of one of the egg holding cups in disconnected or uncoupled position.

40 Fig. 6 is a view of one of the blanks from which the egg cups are constructed.

The improved device includes an open frame, preferably of sheet metal, and having vertical walls 10 and an inwardly di- 45 rected ledge 11 at the lower edge.

Bearing at their ends upon the ledges 11 at the sides of the frame are a plurality of supporting bars, one at each end and the remainder at uniformly spaced relation be- 50 tween the ends.

Each bar is formed from a single strip of metal bent into U-shape transversely to form a trough shaped portion 12 and with the outer portions of the sides bent laterally in opposite directions to form flat seats 13.

Supported upon the seats 13 are a plural-

ity of tray devices each formed from perforated sheet metal and represented as a whole at 14 and with downturned edges 15 to engage in the trough shaped portions 12, 60 as shown in Fig. 3.

By this means the tray members are effectually supported not only from downward but from lateral displacement, while at the same time any individual tray section 65 may be removed or inserted without interfering with the remaining sections, or a broken or impaired section easily renewed.

At some point around the main frame one of the tray sections is wanting, and its place 70 occupied by a swinging door device 16 to provide access to the space below the tray sections.

The door section 16 is formed with one edge turned over as shown at 17, and adapted to receive a pintle rod 18, the latter supported in ears 19 bent inwardly from the adjacent wall 10 of the frame.

The turned over portion 17 of the door is of sufficient length so that when the door 80 member is in full open position, as shown in dotted lines in Fig. 2, the door will drop by gravity until the bend of the portion 17 rests on the adjacent portion of the ledge 11 and thus supports the door in open position and requires the latter to be lifted bodily 85 before it can be closed. The door may thus be quickly disposed in open position with very little effort, but requires to be elevated bodily before it can be closed.

90 The egg holding cups each comprise a band 20 preferably of perforated metal, and bent to conform in outline to an egg and constructed as shown more particularly in Fig. 5. Each band is reduced at the ends with 95 ears 21 extending from each end of the reduced portion, and when the ears interlap as shown in Fig. 4, they can be folded over the adjacent edges of the band.

By this means a simply constructed lock 100 joint is formed for the terminals of the band.

At the center of the band at the side opposite to the terminals just described, the band is formed with two tongues 22 and 23 105 in spaced relation at each edge and formed in the edges of each band at one end is an ear 24, while a recess 25 is formed in each edge of the band at the opposite end.

The bands or "cups" are adapted to be 110 coupled in sets as indicated in Fig. 4, and each set enclosed in a supporting frame 26.

The side ears 22 and 23 and the end ears 24 of the outer cups are bent over the upper and lower edges of the frame, to couple the frame to the sets of cups, while the ears 21 5 and 23 are bent over the adjacent edges of the cups, to couple the cups to the frame and to each other.

The frame 26 is widened at the ends to form runners to hold the nests of cups above 10 the surfaces of the members 14.

The improved device is simple in construction, can be constructed wholly of metal, and of any size and of any number of sections.

15 The preferred embodiment of the invention is disclosed in the drawings and set forth in the specification, but it will be understood that modifications within the scope of the claimed invention may be made in the 20 construction without departing from the principle of the invention or sacrificing any of its advantages.

Having thus described the invention, what is claimed as new is:—

25 1. An incubator tray device comprising an open frame having inwardly directed ledges, supports in spaced relation and bearing upon said ledges, each support being bent into U-shape transversely with the terminals of the 30 sides directed outwardly to form seats, a plurality of tray members of perforated metal supported on said seats and with downturned margins engaging in the trough shaped interior of the supports.

2. A unit for an incubator tray formed of 35 perforated sheet metal with downturned edges, certain of said edges having L-shaped slots, and a support including an L-shaped portion with which said slots engage.

3. In an incubator, a plurality of supports 40 in U-shape transversely with side portions bent laterally to form horizontal seats, and tray units each formed of perforated sheet metal with downturned edges to engage between the sides of the U-shaped supports and 45 bearing on the seats of the same, certain of said downturned edges having L-shaped slots to engage over one side portion of the U-shaped support and one of its seat portions.

4. In an incubator, an open frame having 50 inwardly directed ledges, a plurality of supports bearing upon said ledges, tray sections bearing upon said supports, a rod supported by said frame and spaced from one of said ledges, and a door member with one edge 55 turned over and engaging over said rod to movably couple the door thereto.

5. In an incubator, an egg turning tray comprising a plurality of cup devices for supporting the individual eggs each formed 60 from a sheet of metal strip having bendable ears at the sides and ends, and adapted to be bent over the frame and over the edges of the adjacent cups.

In testimony whereof, we affix our signatures hereto.

HENRY SCHAECHTERLE.
JOHN SCHAECHTERLE.
